UNITED STATES PATENT OFFICE.

PHILIP A. FISCHER, OF NEW YORK, N. Y.

ADJUSTABLE CAP.

Application filed March 16, 1925. Serial No. 16,060.

My invention relates to adjustable caps, the principal object of my invention being to provide a cap having a wide range of adjustment, constructed in such a manner that there are no unsightly folds or creases visible when the cap is being worn.

Adjustable caps as made heretofore are provided with one or more notches or openings along the lower edge of the cap, usually fastened to a corner of the visor of the cap. The displacements of the sections of the body portion of the cap which necessarily takes place when the size of the cap is changed, necessarily takes place in the immediate vicinity of the notch or notches, and experience has shown that the cap wrinkles in an unsightly manner when the constricting straps are drawn together. These wrinkles on the sides of the cap near the corners of the visor, while they may not be uncomfortable to the wearer of the cap, are, nevertheless, very conspicuous and detract from the value of the cap to a considerable extent.

The principal object of my invention is to provide a cap having relatively movable sections which permit a wide range of adjustment, the cap being constructed so that any wrinkles which may form as a result of altering the size of the cap are effectively concealed from view. I have found that this object can be attained by having the relative displacement of the visible portions of the cap body take place at a point near the central portion of the visor rather than at either or both corners of the visor. To this end a portion of the body of the cap is connected to the central portion of the visor and the corners of the visor are left free to assume an easier position in alignment with the lower edge of the side portions of the body of the cap. The adjustment is effected by drawing the side portions of the cap toward each other, thus displacing them with respect to the visor and with respect to the portion of the body of the cap sewed or otherwise connected to the visor. The side portions of the body of the cap are preferably separate from the visor and from that

portion of the body of the cap which is connected to the visor so that the side portions can be readily caused to slide along the visor and along the portion of the body of the cap connected to the visor.

My invention contemplates the provision of means for holding the corners of the visor in alignment with the side portions of the cap body, thus preventing the visor corners from projecting below the lower edge of the body of the cap or projecting up under the body of the cap to an excessive extent. This means may take the form of a strip of stiff material attached either to a visor corner or to the inside of the adjacent portion of the body of the cap. This stiff member cooperates with a loop or pocket carried by the body portion of the cap or by the visor, as the case may be, whereby the several parts are held in proper alignment. Thus, while the corners of the visor are free from the body portion of the cap to the extent that the size of the cap can be readily changed as above described, yet the corners of the visor are, at all times, held in proper position with respect to the lower edge of the body portion of the cap.

In addition to the features above described, my invention includes a yielding fastener for the constricting straps of the cap so that if the wearer of the cap desires to pull it down on his head more than the usual amount, he can do so without readjusting the constricting straps or having the cap fit too snugly on the head. In general, my improved fastener comprises two elements, one attached to each constricting strap, and adapted to cooperate with each other to hold the straps in an adjusted position.

The various objects and advantages of my invention can be best understood by considering the following detailed description, which is to be taken in conjunction with the accompanying drawings, in which

Figure 1 is a front elevation of a cap made in accordance with my invention.

Figure 2 is a side elevation of the cap shown in Figure 1.

Figure 3 is a fragmentary elevation of a portion of the cap shown in Figures 1 and 2, showing details of construction.

Figure 4 is a fragmentary vertical section taken on line 4—4 of Figure 2.

Figure 5 is a fragmentary horizontal section taken on line 5—5 of Figure 2.

Figure 6 is a side elevation of a portion of another embodiment of my improved cap.

10 Figure 7 is a horizontal section taken on line 7—7 of Figure 6.

Figure 8 is a side elevation of another embodiment of my invention.

15 Figure 9 is a side elevation of another embodiment of my invention.

Figure 10 is a fragmentary horizontal section of still another type of cap made in accordance with my invention.

20 Figure 11 is an enlarged transverse view of the fastener shown in Figures 1, 2 and 6.

Figure 12 is an enlarged plan view of the fastener shown in Figure 11, illustrating the manner in which the fastener operates.

25 Figure 13 is an enlarged vertical section view taken on line 13—13 of Figure 11, showing the construction of the fastener.

Figure 14 is a transverse view of a modified form of fastener made in accordance with my invention and

30 Figure 15 is a longitudinal section view of the fastener shown in Figure 14.

The cap shown in Figures 1 to 5 comprise a cap body A and a visor B connected to the cap body and extending along the lower edge thereof. This cap can be adjusted to any one of a considerable number of different sizes and the adjustment takes place at one or more points which are normally well concealed so that any wrinkles or folds 40 caused by the adjustment cannot be seen.

The cap body A can be considered as composed of a plurality of sections. It is convenient to call the portion of the cap body designated by the reference numeral 1 the central section of the cap body and the portions 2 and 3 can be considered as side sections. It is not necessary that these different sections of the cap should consist of different pieces of material or that the sections be sewed together or otherwise joined in any particular manner except that ample provision must be made for changing the size of the cap as hereinafter described. The cap shown in Figures 1 to 5 inclusive is made so that the central section 1 has a portion 4 thereof movable with respect to the side sections 2 and 3 and the adjustment of the size of the cap is effected by changing the relative positions of this portion 4 of the central section of the cap and the side sections 2 and 3. The central section of the cap body, or rather the portion 4 of this section, is connected to the visor whereas the side sections of the cap are separate 60 from the visor, thus leaving the corners of

the visor free to move with respect to the side sections. By drawing together the portions 5 and 6 of the side sections of the cap, as by means of straps 7 and 8, the side sections are caused to slide over the portion 4 of the central section 1 and the size of the cap is made smaller as will be readily understood. It will be noted that the central section, or at least the portion 4 thereof, is of less extent than the visor B or, in other words, the visor is longer than the lower edge of the portion 4 of the central section of the cap. Thus the relative displacement between the central section and the side sections occurs within the limits of that portion of the cap along which the visor extends and, therefore, at points which are normally concealed when the body portion of the cap is folded down over the visor and fastened thereto in the usual manner by means of a snap fastener 9.

From the above description of the manner in which the cap in Figure 1 can be adjusted, it should be apparent that there must be considerable play between the portion 4 of the central section of the cap and the adjacent portion of the side sections 2 and 3 as shown in Figure 1. The central section 1 of the cap is, of course, sewed or otherwise united with the said sections 2 and 3 and above the portion 4 of the central section. As stated above, the central section may be integral with the side sections. The constricting or adjusting straps 7 and 8 may be integral with the side sections 2 and 3 of the cap or may be separate pieces attached to the side sections as may be desired. The straps 7 and 8 may even be the ends of a continuous strip running entirely around the lower edge of the cap as shown in Figure 9. In any event, it will be understood that the constricting straps 7 and 8 are secured to the side sections 2 and 3 and preferably separate from the central sections of the cap. A buckle 10, preferably of the improved form hereinafter described, serves to fix the adjusting strap 7 and 8 in an adjusted position.

In the embodiment of the invention shown in Figures 1 and 5, the portion 4 of the central section of the cap is shown as a piece of material sewed or otherwise connected to the main portion of the central section 1 of the cap. Strips 11 and 12 preferably cut away as shown at 13, are connected to the portion 4 of the central section of the cap and to the corners 14 and 15 of the visor. These strips 11 and 12 serve as a means for holding the corners of the visor in proper position and the several parts of the cap are preferably constructed and arranged so that the corners of the visor are held in a position above the lower edge of the cap body as shown in Figure 2, whereby the corners are concealed from view.

The piece of material shown at 4 and the strips 11 and 12 may consist of material similar to that out of which the body portion of the cap is made or they may consist of other material. If these portions of the cap are made out of material heavier than that composing the body portion of the cap, the visor is held in shape better than it would be if the same material were employed throughout. In Figures 1 and 6, these portions of the cap are shown as made out of relatively heavy material.

In view of the fact that the central section of the cap body to which the visor is connected is of less extent than the visor, it is apparent that in some cases there might be a tendency for the corners of the visor to show below the lower edge of the cap body. In order to prevent this condition and at the same time permit the side sections of the cap to move freely with respect to the corners of the visor in adjusting the size of the cap, I have devised means for holding the corners of the visor in proper alignment with respect to the lower edge of the cap. In Figure 6, I have shown such a means consisting of a piece of stiff material 16 such as card-board or celluloid, or the like, fixed with respect to the visor corner 14 and cooperating with a loop 17 or pocket formed in the lining 18 of the cap. The strip of material 16 fits loosely in the loop or opening 17 and this opening is preferably located at a point somewhat remote from the lower edge of the cap, so that the extreme corner of the visor is always concealed from view. The strip 16 can be fastened directly to the portion 13 of the cap body, which is connected to the central section 1 of the cap. The corner 14 of the visor being connected to the portion 13 of the cap is connected to the strip 16 whereby this strip partakes of any relative movement between the side portion of the cap and the corner 14 of the visor.

The cap shown in Figure 8 is substantially the same as that shown in Figure 6 except for the means which holds the visor corners in proper alignment with the lower edge of the cap. In Figure 8 the stiff member 16 is secured to the side section 3 of the cap instead of to the visor or to any part connected to the visor. A piece of material 13', connected to the visor, carries one or more loops 19' or pockets which cooperate with the stiff member 16 to hold the visor and the lower edge of the cap in position.

The central section 1 of the cap shown at Figure 8 instead of being separate from the portion 20 of the side section 3 of the cap up to the point 21, as is the case with the cap shown in Figures 1 and 6, is integral with the side section. Relative movement between the side section 3 and the central section 1 is permitted by providing a fold or pleat 22 in the material as shown in Figure 8.

In Figure 10, I have illustrated a cap which is substantially the same as that shown in Figures 1, 6 and 8, except that the lining 18' is connected to the central section 1 of the cap and extends continuously across to the side section 3. A fold or pleat 23 is formed in the lining at the point where the central section and the side section 3 come together, so as to permit ample adjustment of the size of the cap.

In Figures 11 to 13 inclusive, I have illustrated a form of buckle or fastener adapted to secure the adjusting or constricting straps 7 and 8 together in any desired position. This form of buckle is shown on the caps illustrated in Figures 1, 2 and 6. In general, the fastener comprises two parts, one fixed to each of the strap pieces. A stiff member 24, which can be made out of card-board, celluloid or other stiff material, is carried inside of the strap 8. This member 24 has a number of notches 25 along one or preferably both edges adapted to receive portions of the fastener element 26 carried by the strap 7. This element is preferably made out of wire or other material which will yield to some extent when any considerable stress is applied to the adjusting straps. The element 26 is provided with two spring arms 27 and 28, each having a bent portion 29, adapted to force the edges of the strap 8 into the notches on the stiff member 24. Spring arms 27 and 28 may be crossed as shown in Figure 1 so as to bring the bent portions 29 directly opposite each other or the construction shown in Figures 11 to 13 inclusive can be employed. The fastening elements 26 and 24 can be separated by simply applying pressure to the sides of the element 26 as indicated by the arrows in Figure 12. With the parts in position shown in Figure 12, the straps 7 and 8 can be moved along each other to change the size of the cap.

In Figures 14 and 15, I have illustrated another form of fastener adapted to hold the adjusting straps 7 and 8 in an adjusted position. This fastener comprises a stationary element 30 and a movable element 31. These two elements are fastened together by the pivot connection shown at 32. The strap 7 is connected to the movable element 31 and the other strap 8 is adapted to move between the elements 30 and 31 when the elements are in the position shown in Figure 14. If tension is applied to the straps 8 while the elements of the fastener are in the position shown in Figure 14, the movable element 31 closes down on to the strap 8 so as to force the sharp projections 33 on the element 31 into the material of the strap 8, as shown in Figure 15. The movable element 31 has an upturned portion 34 which can be readily grasped when it is desired to release the fastener. The strap

7 is attached to a cross-bar 35 which forms part of the movable element 31.

It is to be understood that my invention is not confined to the particular embodiments illustrated and described but includes such modifications thereof as fall within the scope of the appended claims. Various details such as the manner in which the cap body is made, whether out of a singel piece or a number of pieces of material, the particular manner in which the front central section of the cap is made movable with respect to the side sections, and the manner in which the constricting strap or straps are applied to the cap body can be varied within wide limits without sacrificing the advantages of my invention.

I claim:

1. A fastener for adjustable caps or the like, comprising a member having a plurality of notches therein, and a second member partially looped about said notched member and having a lug adapted to engage the notched member to lock the two members together.

2. A fastener for adjustable caps or the like, comprising a member having a plurality of notches therein, and a second member partially looped about said notched member and having a spring-pressed lug adapted to engage the notched member to lock the two members together.

3. A fastener for adjustable caps or the like, comprising a member having a plurality of notches along two edges thereof, and a second member surrounding said notched member and having two spring arms and a lug carried by each arm, the spring arms being arranged so that the lugs carried thereby engage notches in the

two notched edges of the first mentioned member.

4. A fastener for adjustable caps or the like, comprising a member having a plurality of notches along two edges thereof, a flexible sheath enclosing said member and covering the notches along the edges thereof, and a member having two spring arms and a lug carried by each arm, the said spring arms being arranged so that the lugs carried thereby press portions of said sheath into notches in said first mentioned member whereby the two members are locked together.

5. A fastener for adjustable caps or the like comprising a blade member having a plurality of notches therein, and a member having a spring arm partially looped about said blade member and having a bent portion engaging in said notches to lock the two members together.

6. A fastener for adjustable caps or the like comprising a blade member having a plurality of notches along two edges thereof, and a double spring-arm member surrounding said blade member and having bent portions engaging in said notches in the two edges of said blade member.

7. A fastener for adjustable caps or the like comprising a blade member having a plurality of notches along its two edges, and a double spring arm member surrounding said blade member and having bent portions engaging in said notches, the arms of said spring member being oppositely looped about said blade member whereby the fastener can be released by pressing the spring arms together.

In testimony whereof I affix my signature.
PHILIP A. FISCHER.
